(57) **CLAIM**

The ornamental design for eyewear, as shown.

DESCRIPTION

FIG. 1 is a front perspective view of eyewear of the present invention;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another rear perspective view thereof showing an unclaimed tool usable to install and remove a lens; and showing the nose piece in the state of being removed.

The broken lines are directed to features of the eyewear that form no part of the claimed design.

1 Claim, 9 Drawing Sheets
